CIGARETTE HOLDER

Byron R. McCready, Garden City, Mich.

Application May 28, 1949, Serial No. 96,105

7 Claims. (Cl. 131—175)

This invention relates to a cigarette holder.

It is an object of this invention to produce a cigarette holder which is constructed so as to give a smoke which is very mild and which has the flavor produced by burning freshly roasted tobacco.

A further object of the invention resides in the provision of a cigarette holder which has a very attractive appearance and which is provided with a bowl which automatically collects the ashes as the cigarette burns.

It is a further object of the invention to produce a cigarette holder having a bowl which substantially encloses the burning end of the cigarette so that the dangers of flying sparks, lighted ashes, and the like usually encountered in smoking cigarettes are eliminated in the holder of my design. The provision of a bowl which substantially encloses the burning end of the cigarette also permits the cigarette to be left unattended without any danger of causing a fire.

In the drawings:

Figure 1 is a perspective view of my cigarette holder.

Figure 2 is a perspective view of my cigarette holder with the bowl in the opened condition and with parts broken away to show the cigarette feeding means in the stem.

Figure 3 is a sectional view taken substantially along the lines 3—3 in Figure 1.

Figure 4 is a sectional view taken substantially along the lines 4—4 in Figure 3.

Figure 5 is a fragmentary view of a holder of modified construction.

Referring to the drawings, the holder comprises a stem 10 having a bit 11 at one end and a bowl 12 at the other end. Stem 10 comprises a tubular body 13 which is slightly larger in diameter than a cigarette. The bit 11 has at one end a mouth piece portion 14 having an end which is adapted to be gripped between the smoker's teeth and a cylindrical portion 15 at the other end slidably arranged within the body 13 of stem 10. At its enclosed end the bit 11 is provided with a cup member 16 which has a bearing contact with the inner surface of body 13 and which is adapted to receive one end of cigarette 17 so that when the bit is moved axially within stem 10 the cigarette moves with it. Cup member 16 has a larger external diameter than cylindrical portion 15.

A passage 18 extends through the bit 11 from mouth piece portion 14 to a cup 16 so that when the smoker draws on the mouthpiece he may draw through the cigarette. A light coil compression spring 19 is arranged in the stem 10 in the clearance space between body 13 and the outer surface of the cylindrical portion 15. A spring 19 has one end bearing against a collar 20 inserted in one end of body 13 and has its other end acting against the closed end of cup 16. This arrangement tends to automatically feed the cigarette into the bowl 12 as the cigarette burns.

Bowl 12 is preferably formed as two substantially spherical half sections 22 and 23 which are hinged together as at 24 so that when the upper section 22 is pivoted to the closed position the burning end of the cigarette is substantially enclosed by the bowl. The bowl may, if desired, be provided with a shape other than spherical. The bowl 12 is preferably formed of a material which conducts heat readily such as aluminum, brass, or the like and is dimensioned such that the heat generated by the burning end of the cigarette maintains the bowl relatively hot.

2

At its end opposite the bit 11 the body 13 is cut away as at 25 around at least the upper half of the body so that when the top section 22 of the bowl is pivoted to the opened position shown in Figure 2 the cigarette may be grasped by the fingers in order to insert it within the cup 16 of the bit 11. A ribbed portion 26 around the lower half of body 13 forms a connection between bowl 12 and body 13. This connecting portion is perforated or otherwise apertured as at 27 as seen in Fig. 4, so as to ventilate the cigarette at this point and at the same time prevent the conduction of too much heat from bowl 12 to the body portion 13 of the stem. The connecting portion 26 extends into the bottom section 23 of bowl 12 and provides a semi-cylindrical seat 28 for the end of the cigarette within the bowl. The top portion 22 of the bowl 12 has secured thereto a semi-cylindrical cage 30 which when the top section 22 is pivoted to the closed condition cooperates with the connecting portion 26 of the stem to provide a substantially open grill work around that portion of the cigarette extending between body 13 and bowl 12. At its free end the cage 30 is fashioned with a pair of arcuately shaped resilient fingers 31 which snap over body 13 and retain the top section 22 in the closed position. At its opposite end the cage 30 is provided with an imperforate collar 32 which cooperates with the seat member 28 at the corresponding end of connecting portion 26 to form a continuous collar of substantial width around a portion of the cigarette within the bowl.

In order to promote burning of the cigarette, the bottom 23 of the bowl is provided with a plurality of apertures 33, 34, and 35. These apertures as is shown in Figures 3 and 4, are positioned adjacent the seat 28 so that the air which is drawn in through these apertures 33, 34, and 35 comes into direct contact with the seat 28 and thereby is heated before it comes into contact with the hot smoke in the bowl. When the smoker is not drawing through the cigarette, it burns more slowly and the smoke from the burning end of the cigarette is exhausted through a larger port 36 located centrally of the bowl in the top section 22. It will be seen that the apertures 33, 34, and 35 cooperate with the exhaust port 36 to provide a natural draft upwardly through the bowl so that the cigarette continues to burn slowly even though a draft is not drawn through the cigarette through passage 18. A generally circular spring clip 38 having a pair of opposed fingers 39 is frictionally retained within bottom 23 with the fingers 39 spaced apart and engaging the burning end of the cigarette so as to position it preferably at approximately the center of the bowl. Fingers 39 serve as stops against which the burning end of the cigarette is held by the pressure of spring 19. Said clip 38 is fashioned so as to be removable from the bottom 23 to facilitate cleaning the bowl when necessary.

When the bowl is formed with a spherical shape as shown it is preferably provided with small legs 40 which enable positioning the holder upright on a flat surface such as a table top or the like. Legs 40 also prevent the hot bowl from burning or scorching the surface on which it may be positioned.

When it is desired to insert a cigarette in my holder, spring fingers 31 are snapped upwardly from around the body 13 and the top section 22 of the bowl is pivoted to the opened position shown in Figure 2. A cigarette is then inserted within the body 13 with one end engaged by the fingers 39 of clip 38. The cigarette is then grasped as at the cut away portion 25, and the bit 11 is pushed in a direction inwardly of the stem so as to engage the other end of the cigarette within the cup 16. The top section 22 is then pivoted to the closed position and the cigarette is ready for smoking. The tobacco may be ignited by holding a lighted match over the exhaust port 36 and drawing inwardly on the bit so as to produce a draft through the cigarette and the passage 18 in the bit. As the cigarette burns the ashes fall into the bottom section 23 of the bowl and the spring 19 urges the cup 16 in a direction towards the bowl so as to progressively feed the cigarette into the bowl with the burning end of the cigarette engaged and positioned by the fingers 39 of the clip 38. A depending flange 41 around the exhaust port

36 tends to prevent the ashes and burning cinders from falling out of port 36 if the bowl is accidentally inverted.

It will be observed that the bowl 12 is substantially enclosed and therefore becomes relatively hot as the cigarette burns. I have found that for the best operation of my cigarette holder it is essential that the bowl be maintained relatively hot.

It is desirable to maintain bowl 12 relatively hot when the cigarette is burning for several reasons. In the first place, a more complete burning of the tobacco is effected, but even more important is the fact that if the bowl is maintained at a relatively high temperature, the moisture, tars, resins, and nicotine in the smoke will not be condensed on the inner surface of the bowl as they pass from the cigarette out through the exhaust port 36. If the bowl is too large or is maintained at a relatively low temperature for other reasons, then objectionable condensation occurs which not only imparts a foul odor to the cigarette holder and the smoke, but also cakes up on the inner surface of the bowl. I have also found that by maintaining the interior of the bowl at a relatively high temperature the flavor of the smoke is greatly improved and resembles the flavor imparted to smoke by burning freshly roasted tobacco. I believe this may be due to the fact that the tobacco within the bowl just to the rear of the burning end of the cigarette is heated to a roasting temperature.

It will be appreciated, of course, that the temperature of the smoke drawn through the cigarette would be normally higher than with cigarette holders of conventional design. However, as the hot smoke drawn through the cigarette passes the zone surrounded by the open grill work provided by cage 30 and the connecting portion 26, it is rapidly cooled. This not only cools the smoke which the smoker eventually draws into his mouth through passage 18 but also condenses a substantial portion of the moisture, tars, resins, nicotine, and etc. in the smoke. This condensation within the cigarette is very marked. The cigarette paper is wetted to a brownish color around this portion of the cigarette and especially at the edge of the bowl.

The seat 28 and the collar 32 which surround the cigarette as it enters the bowl serve not only to transmit heat to the tobacco at this point but also act to prevent burning of the tobacco and the cigarette paper beyond this point and thereby promote complete burning of the tobacco at the end of the cigarette within the bowl. The seat 28 also serves to heat the air entering the bowl through the vents 33, 34, and 35 so that this relatively cool air will not come in direct contact with the warm smoke and produce condensation.

It will thus be seen that I have provided a cigarette holder which permits smoking in a convenient manner and at the same time possesses safety features not found in other cigarette holders with which I am familiar. The provision of a substantially enclosed bowl also eliminates the danger of flying lighted ashes or cigarette cinders which is encountered with cigarette holders of conventional design. It will be noted in addition that if the cigarette holder with a lighted cigarette therein is placed into a confined space such as a pocket or a purse, the supply of air thereto for combustion will be cut off and the burning end of the cigarette will be smothered. In any event, the seat 28 and the collar 32 prevent burning of a cigarette beyond a minimum predetermined length so that if the lighted cigarette is left unattended or the holder is accidentally dropped such as by a person smoking in bed, the cigarette will burn down to a butt of predetermined length and then will be automatically extinguished. This minimum length is determined by the distance between cup 16 and seat 28 when the enlarged portion of bit 14 abuts against collar 20.

Although the provision of a substantially enclosed bowl produces what I believe to be the better smoke, I have found that a relatively flavorful and cool smoke is also obtained when the bowl is not substantially closed and even when a bowl member is entirely omitted. The holder may if desired be constructed with only the lower section 23 of the bowl in which case the bowl serves merely to collect the ashes which fall off the burning end of the cigarette. Or if desired the bowl may be omitted entirely as is shown in Figure 5. In this holder of modified construction the stem 42 is constructed substantially the same as the holder stem 10 shown in Figure 2. The fingers 43 which engage the burning end of the cigarette are fashioned as a removable cap member 44 which is ar-

ranged to slip over an imperforate collar 45 at the end of the stem. The collar 45 surrounds the end portion of the cigarette and is spaced from the body of stem 42 by the open grill work 46.

5 I claim:

10 1. In a smoking device such as a cigarette holder of the type having a hollow tubular stem in which a cigarette is adapted to be positioned and advanced towards one end of the stem as a cigarette burns and thereby shortens in length, a hollow bowl at said end of said stem, said bowl being of generally regular shape and having an internal dimension substantially greater than the transverse dimension of said tubular stem, means within said bowl forming a stop for positioning the burning end of a cigarette 15 within the bowl as the cigarette is advanced in said stem, said means being arranged to maintain the burning end of a cigarette in a predetermined position within said bowl spaced from the walls of the bowl, said bowl being divided into an upper half section and a lower half section 20 pivotally connected together and cooperating when juxtaposed to form a generally closed bowl at the end of said stem, said upper and lower bowl sections having apertures therein, the aperture in the upper bowl section being located directly above the burning end of a cigarette positioned within said bowl, the remaining portion of the wall of said upper bowl section being imperforate, the apertures in the lower bowl section being offset from the portion of the wall of said lower bowl section directly below the burning end of a cigarette positioned within said bowl, the area of the aperture in said upper bowl section being substantially greater than the area of the apertures in said lower bowl section.

25 2. The combination set forth in claim 1 wherein said stem and bowl are provided around their line of connection with an internal collar aligned coaxially with said stem, said collar being dimensioned to circumferentially engage the outer surface of a cigarette positioned within said stem, said collar extending inwardly of said bowl toward the mouthpiece and said apertures in said lower bowl section being disposed closely adjacent and below the lower portion of said collar.

30 3. In a smoking device such as a cigarette holder of the type having a hollow tubular stem in which a cigarette is adapted to be positioned and advanced towards one

35 45 4. In a smoking device such as a cigarette holder of the type having a hollow tubular stem in which a cigarette is adapted to be positioned and advanced towards one end of the stem as a cigarette burns and thereby shortens in length, a hollow bowl at said end of said stem, said bowl being of generally regular shape and having an internal dimension substantially greater than the transverse dimension of said tubular stem, means within said bowl forming a stop for positioning the burning end of a cigarette within said stem, said means being arranged to maintain the burning end of a cigarette in a predetermined position within said bowl spaced from the walls of the bowl,

50 55 5. In a smoking device such as a cigarette holder of the type having a hollow tubular stem in which a cigarette is adapted to be positioned and advanced towards one end of the stem as a cigarette burns and thereby shortens in length, a hollow bowl at said end of said stem, said bowl being divided into an upper half section and a lower half section pivotally connected together and cooperating when juxtaposed to form a generally closed bowl at the end of said stem, said upper and lower bowl sections having apertures therein, the aperture in the upper bowl section being located directly above the burning end of a cigarette positioned within said bowl, the remaining portion of the wall of said upper bowl section being imperforate, the apertures in the lower bowl section being offset from the portion of the wall of said lower bowl section directly below the burning end of a cigarette positioned within said bowl, the area of the aperture in said upper bowl section being substantially greater than the area of the apertures in said lower bowl section, said body being generally circular in horizontal section, said means for positioning the burning end of a cigarette in said bowl comprising a resilient metal strip shaped into the form of a segment of a ring having a diameter corresponding generally to the largest diameter of said bowl, said ring being horizontally disposed and frictionally engaged with the inner surface of the wall of said lower bowl section, said ring segment having at the ends thereof a pair of fingers extending inwardly towards the center of the bowl and against which the burning end of a cigarette is arranged to abut when advanced axially through said

60 65 70 75 80 stem in the direction of said bowl.

4. In a smoking device such as a cigarette holder of the type having a hollow tubular stem in which a cigarette is adapted to be positioned and advanced towards one end of the stem as a cigarette burns and thereby shortens in length, a hollow bowl at said end of the stem, said bowl

being generally circular in cross section and being apertured to admit air to the burning end of the cigarette and means within said bowl forming a stop for positioning the burning end of a cigarette within the bowl as the cigarette is advanced in said stem comprising a resilient metal strip shaped into the form of a segment of a ring having a diameter corresponding generally to the largest diameter of said bowl, said ring being horizontally disposed and frictionally engaged with the inner surface of the wall of said bowl, said ring segment having at the ends thereof a pair of fingers extending inwardly towards the center of the bowl and against which the burning end of a cigarette is arranged to abut when advanced axially through said stem in the direction of said bowl.

5. In a smoking device such as a cigarette holder of the type having a hollow tubular stem in which a cigarette is adapted to be positioned and advanced towards one end of the stem as a cigarette burns and thereby shortens in length, a hollow bowl at said end of said stem, said bowl comprising two portions substantially corresponding in shape and having an internal dimension substantially greater than the transverse dimension of said tubular stem, means within said bowl forming a stop for positioning the burning end of a cigarette within the bowl as the cigarette is advanced in said stem, said means being arranged to maintain the burning end of a cigarette in a predetermined position within said bowl spaced from the walls of the bowl and from the end of said stem, said bowl and stem being provided around their line of connection with an internal collar aligned co-axially with said stem, said collar being dimensioned to circumferentially engage the outer surface of a cigarette disposed within said stem

around a portion thereof spaced axially inwardly from said stop to provide a tobacco burning zone at the end of the cigarette of relatively short length as compared with the length of the cigarette, said collar extending inwardly of said bowl and said bowl toward the mouthpiece being provided with apertures at least some of which are disposed below and adjacent said collar for directing streams of air against said collar.

6. The combination set forth in claim 5 wherein said bowl is provided with an aperture disposed above the burning end of the cigarette positioned within said stem, said last mentioned aperture being relatively large as compared with the apertures provided for directing streams of air against said collar.

7. The combination called for in claim 6 including a depending flange within said bowl extending circumferentially around said relatively large aperture.
